NORMAN L. SNOW, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Application filed May 25, 1925. Serial No. 32,799.

The invention relates to boiler cleaners and refers more particularly to an improved blower construction particularly adapted, though not necessarily so limited, to remove 5 slag deposits and the like from parts of the boiler heating surfaces such as the boiler tubes.

The invention provides a blower element which is adapted to be projected under the 10 influence of the cleaning fluid pressure transversely of the fire chamber to direct one or more jets of cleaning fluid against slag deposits which accumulate especially on the lowermost rows of boiler tubes nearest to 15 the combustion chamber of the boiler. The blower element may, however, be located in any portion of the boiler desired and is equally adapted to remove soot and other 20 deposits or accumulation on various parts of the boiler.

A further provision of the invention resides in a discharge nozzle head which may have two discharge nozzles of substantially 25 the same size whereby the nozzle head is balanced, thus avoiding any thrusts transversely of the blower element. Such a construction also readily adapts itself to the 30 foresaid operation in travelling between the first and second rows of tubes or between other 35 of the tubes of the boiler whereby the blower element may be reciprocated or partially rotated 180° or rotated 360°. In either instance the effect will be to effectively utilize 40 the discharged cleaning fluid jets for all angles of rotation of the cleaning element and to obtain 360° of effective blowing for 45 180° of rotation of the blower element.

A still further feature of the invention resides in the provision of a sectional blower 50 element adapted to be projected under the influence of the cleaning fluid with means for controlling the movement or travel of the blower element. By reason of such construction it is possible to clean parts of the 55 boiler at points intermediate the extreme limits of travel of the blower element.

Other features of the invention reside in the provision of a reduction gear drive for 60 rotating or reciprocating the blower element; the provision of sections which are inter-

connected to permit relative longitudinal movement but adapted to rotate together; and the provision of bearing surfaces at the points of support between the successive sections, which surfaces are decreased on successive 55 outward sections of the blower element.

With these and other objects in view, the invention resides in the novel features of construction and combination and arrangements of parts as more fully hereinafter described and claimed.

Referring to the drawings:—

Figure 1 is a diagrammatic view of a boiler showing one location of my blower element;

Figure 2 is a sectional elevation view of 65 one form of my boiler cleaner showing the sections of the blower element is retracted position;

Figure 3 is a sectional view along 3—3 of 70 Figure 2;

Figure 4 is an end elevation view showing 75 the chain drum and the parts associated therewith;

Figure 5 is a fragmentary elevation view of the brake mechanism located at 5—5 of 75 Figure 4;

Figure 6 is a sectional view along 6—6 of 80 Figure 2;

Figure 7 is a view showing the sections of 85 the blower element in projected position;

Figure 8 is a sectional view along 8—8 of 90 Figure 7;

Figure 9 is a sectional view illustrating a 95 modified form of blower head and element;

Figure 9^a is a sectional view along 9^a—9^a 100 of Figure 9;

Figure 10 is a view corresponding to Figure 1 showing one position for locating the blower shown in Figure 9, and

Figure 11 is a fragmentary view in cross 105 section illustrating a further modified construction of a blower head.

Referring to the drawings in which like 110 reference characters indicate corresponding parts, reference character A indicates a boiler of any usual or preferred construction having a plurality of sets or rows of boiler tubes B. C indicates a baffle suitably located with respect to the boiler tubes B to form the passes E and E'. F indicates a blower which, 115

as shown in Figure 1, may be located between the lowermost row of boiler tubes B' and the adjacent row of boiler tubes B_2 . In detail the blower F may be constructed as shown in Figure 2, in which 10 indicates the blower head having a cleaning fluid inlet 11 for conducting any suitable cleaning fluid from a source of supply of cleaning fluid and thence to the lower element G . This lower element 10 may be formed of a plurality of sections, the outermost of which as indicated at 12 is preferably rotatable within the blower head 10 but nonprojectile. The section 12 may be supported at one end by the roller bearings 13. 14 indicates a gear carried by the section 12 at the other end thereof, the gear 14 meshes with a pinion 15 driven by a sheave 16 through a shaft 17 mounted to rotate in the blower head 10. The sheave 16 may be actuated by the usual chain 17' or other preferred means. 18 indicates a thrust bearing adapted to take up the thrust axially of the blower element when the same is projected under the influence of the cleaning fluid as will be presently apparent. 19 indicates a shaft mounted transversely of the blower head 10, the shaft rotatably mounting a guide pulley 20 over which is adapted to pass a flexible member such as a chain or the like 21. 22 represents fixed lugs or guide members for maintaining the proper position of the chain 21 during its travel over the guide pulley 20. 23 indicates the innermost section of the blower element G , the section 23 carrying a blower nozzle-head 24 preferably formed with the discharge nozzles 25 and 26. These nozzles may have their axes arranged at an angle with the axis of the blower element and may be of the same size whereby the blower element will be in a balanced condition free from side thrusts or thrusts in a direction transversely of the axis of the blower element. 27 indicates a spider rigidly carried by the section 23. The chain 21 has one end attached to the spider 27 preferably through a swivel joint or connection 28. As shown in Figure 8, the sections of the blower element G are provided with registering flattened portions to permit their relative longitudinal movement but 50 to cause them to rotate together as a unit. 29 represents a drum housing within which is mounted the chain drum 30 for receiving the flexible member or chain 21. 31 represents a shaft extending transversely through the drum housing 29 for mounting the drum 30. The shaft 31 is provided with an extension outside of the drum housing and upon this extended portion of the shaft 31 a brake drum or wheel 32 is mounted to rotate with the shaft. 33 is a brake band which is arranged to frictionally engage the circumference of the brake drum 32 and restrain the rotation thereof. The brake band 33 has one end fixed at 34 as best shown in Figure 5 and has its other end formed with a

projection 35. 36 is a tension rod carrying the rotatable hand control member 37. The latter member is formed with a portion engageable with the projection 35 whereby upon rotation of the hand control member 37 the free end of the brake band will be drawn toward the fixed end to apply a braking force to the drum 32 in a manner which will be readily apparent.

As shown in Figure 1 the blower is preferably located between the lowermost row of boiler tubes and the row of tubes adjacent thereto in order to effectively remove the slag and other accumulations from this portion of the boiler. In operation with the parts as shown in Figure 2 cleaning fluid is admitted to the blower head causing a piston effect at the nozzle head 24 thereby tending to urge the successive sections of the blower element G into the projected position as shown in Figure 7. By reason of the hand control member 37 the operator may control the rate of rotation of the brake drum 32 and hence the chain drum 30 which rotates in accordance with the travel of the various successive sections of the blower element by reason of the chain 21 connected with the section 23. It is therefore apparent that the operator may not only control the rate at which the sections of the blower element are projected but if desired the blower nozzle head 24 may be brought to a complete standstill at any point intermediate the extreme points of travel of the nozzle head. In either the extreme points of travel of the nozzle head or at any point intermediate thereof the nozzle head may be rotated or reciprocated by reason of the sheave 16. Movement of the latter sheave is transmitted through shaft 17, pinion 15 and gear 14, to act upon the rotatable section 12 whereby a corresponding movement is transmitted through the various sections of the blower element and thence to the nozzle head 24.

In the projected position of the sections as shown in Figure 7 the bearing surfaces at points of support between the successive sections such as indicated at H are decreased outwardly of the blower element. By reason of such construction the sections of the blower element are maintained in a rigid condition free from axial sag or distortion.

By reason of the discharge nozzle head having the two discharge nozzles of substantially the same size the nozzle head and hence the blower element is balanced against side thrusts as aforesaid, also such construction adapts itself to the aforesaid operation in travelling between adjacent rows of boiler tubes whereby the blower element may be reciprocated or partially rotated through an arc of 180° or rotated 360° . In either instance the effect will be to utilize the discharged cleaning fluid jets from the two nozzles for all angles of rotation of the clean-

ing element thereby obtaining 360° of effective blowing for 180° of rotation of the blower element.

At the end of the blowing period the sections of the blower element may be retracted to the position shown in Figure 2 by actuation of the crank 38 mounted on the shaft 31, the retraction being accomplished by reason of the chain 21 being wound about the chain drum 30.

It will be noted that I have provided a reduction gearing through which rotation of the blower nozzle head is accomplished, the reduction gearing being carried by the blower head. I have further provided a blower construction in which the blower element is provided with a chain winding drum and brake control mechanism arranged closely adjacent the blower head.

Instead of the aforesaid balanced nozzle head construction I may provide a nozzle head having one main discharge nozzle and an oppositely directed smaller discharge nozzle which affords a practical balance for the nozzle head without material waste of the cleaning fluid discharged from the smaller balancing discharge nozzle. In this instance it is preferable to cause the blower element to travel below the bottom row of tubes and to reciprocate or partially rotate the blower element 180°. In Figure 10 I have shown the blower F' arranged in accordance with such a construction, the blower F' being shown located below the lowermost row of tubes B'.

Referring to Figure 9 I have shown a modified construction of a blower having a blower nozzle head especially adapted for use where the blower is positioned as shown in Figure 10. In this construction 10^a indicates the blower head provided with the rotatable section 12^a adapted to be rotated as before by reason of a gear 14^a driven from the sheave 16^a through a shaft 17^a and pinion 15^a.

24^a represents the discharge nozzle head carried by the section 23^a, the nozzle head being provided with a main cleaning fluid discharge nozzle 25^a and a second nozzle 26^a of considerably less discharge capacity than the main nozzle. These nozzles are as before arranged at an angle with the longitudinal axis of the blower element, the main nozzle 25^a being directed upwardly for discharging a jet of cleaning fluid against the row of boiler tubes B' and parts associated therewith, while the other nozzle 26^a is directed downwardly in the combustion chamber. In this construction the main nozzle is adapted

60 to remove slag deposits and the like from the boiler tubes, by imparting a rotary or reciprocating motion to the nozzle head by reason of the sheave 16^a. The nozzle head is preferably reciprocated through an arc of 180° so as to effectively utilize the jet of

cleaning fluid discharged therefrom at all times. The discharge nozzle 26^a in this instance substantially balances the blower element against side thrusts, while at the same time because of its reduced size, it does not materially waste the cleaning fluid.

70 In the construction shown in Figure 9 I have provided a flexible member for controlling the movement of the sections of the blower element, which flexible member is illustrated in this instance as a wire 21^a connected at one end through a swivel joint or connection 28^a to the element 23^a. 27^a represents a spider carried by the element 23^a for mounting the swivel joint 28^a and at the same time providing a series of openings 39 for the passage of cleaning fluid. In this construction the drum 30^a and the braking mechanism associated therewith may be located outside of the passage of the cleaning fluid as shown in Figure 9, the wire 21^a passing through a suitable stuffing box 40. The drum 30^a and the brake mechanism associated therewith are adapted to control the projection and retraction of the blower element in substantially the same manner as before described.

80 Referring to Figure 11 I have shown a still further type of blower head in which the reduction gearing for rotating the blower nozzle head is mounted outside of the path of the cleaning fluid. In this instance the blower head 10^b is adapted as before to house the rotatable section 12^b of the blower element. The section 12^b is provided with a portion extending forwardly 90 through the blower head as indicated at 12^c. For supplying cleaning fluid to the blower nozzle head the section 12^b may be provided with one or more ports 41. 18^b indicates a thrust bearing for taking up the axial thrust due to the piston effect produced by the cleaning fluid acting in projecting the sections of the blower. The portion 12^c of the section 12^b is adapted to carry the gear 14^b driven by sheave 16^b through the pinion 15^b. In this instance the reduction gearing between the sheave 16^b and the section 12^b is mounted outside of the path of the cleaning fluid, the reduction gearing being incorporated or carried by the blower head 10^b.

95 By the term "rotate" as used throughout the specification and claims I mean one or more complete or partial rotations of the blower element.

100 What I claim as my invention is:

1. In a boiler cleaner, an extensible and retractable lower element mounted for rotation, means for supplying a cleaning fluid to said blower element, the cleaning fluid acting on said blower element and tending to extend the same, a single blower nozzle head carried by said blower element and movable relative to the boiler surfaces to be cleaned upon the extension of the blower element, means for 115 checking the extension of said blower ele- 120

ment by the cleaning fluid at a plurality of desired points to locate the said blower nozzle head in a plurality of blowing positions, means for rotating the blower element with the blower nozzle head in any one of its blowing positions, and a flexible element for returning the blower element to its retracted position.

2. In a boiler cleaner, an extensible and retractable blower element mounted for rotation, means for supplying a cleaning fluid to said blower element, the cleaning fluid acting on said blower element and tending to extend the same, a flexible element for returning the blower element to its retracted position, a single blower nozzle head carried by said blower element and movable relative to the boiler surfaces to be cleaned upon the extension of the blower element, a brake cooperating with said flexible element for checking the extension of said blower element by the cleaning fluid at a plurality of desired points to locate the said blower nozzle head in a plurality of blowing positions, and means for rotating the blower element with the blower nozzle head in any one of its blowing positions.

3. In a boiler cleaner, a blower element formed of a plurality of telescopic sections, means for supplying a cleaning fluid to said blower element, the cleaning fluid acting on said blower element and tending to project the sections of the same, a single blower nozzle head carried by the innermost section of said blower element, said blower nozzle head being movable with said section relative to the boiler surfaces to be cleaned upon projection of the section, a flexible element connected to the innermost section of said blower element, a drum cooperating with said flexible element to provide means for retracting the blower element, a brake associated with said drum for checking the projection of said innermost section at a plurality of desired points to locate the said blower nozzle head in a plurality of blowing positions, and means for rotating the blower element with the blower nozzle head in any one of its blowing positions.

50. In testimony whereof I affix my signature.
NORMAN L. SNOW.
